UNITED STATES PATENT OFFICE.

CHARLES L. ZIEGLER, OF BOSTON, MASSACHUSETTS.

DESIGN FOR A BUCKLE.

SPECIFICATION forming part of Design No. 22,504, dated June 6, 1893.

Application filed April 7, 1893. Serial No. 469,473. Term of patent 7 years.

To all whom it may concern:

Be it known that I, CHARLES L. ZIEGLER, a citizen of the United States, residing at Boston, in the county of Suffolk and State of Massachusetts, have invented and produced a new and original Design for a Buckle, of which the following is a specification, reference being had to the accompanying drawing, showing a part thereof.

10 The drawing represents a front elevation of a buckle showing my design.

The leading feature of my design consists in an elongated loop a , a flattened tongue-like portion a' depending therefrom and having a fluted shell-like end a^2 provided with a scalloped edge b , and a base b' extended beyond

the portion a' , between the loop and shell-like end a^2 .

The design shown makes a very attractive buckle in general configuration and appearance.

I claim—

The design for a buckle, substantially as shown and described.

In testimony whereof I have signed my name to this specification in the presence of two subscribing witnesses.

CHARLES L. ZIEGLER.

Witnesses:

JOHN C. EDWARDS,
FREDERICK L. EMERY.
